UNITED STATES PATENT OFFICE.

LEROY P. CLUTTER, OF DEER LICK, PENNSYLVANIA.

EXCAVATOR.

1,107,899.

Specification of Letters Patent. Patented Aug. 18, 1914.

Application filed June 17, 1911. Serial No. 633,666.

To all whom it may concern:

Be it known that I, LEROY P. CLUTTER, a citizen of the United States of America, residing at Deer Lick, in the county of Greene and State of Pennsylvania, have invented certain new and useful Improvements in Excavators, of which the following is a specification, reference being had therein to the accompanying drawing.

10 This invention relates to improvements in excavators.

Among the objects of my invention are the following: (1) To provide a device of this character which may be readily applied to an ordinary type of motor such as a portable or traction steam engine. (2) To provide a device of this character having a traveling excavating bucket controllable by a single operator without affecting the operation of the 20 motor. (3) To provide a device adapted for pivotal movement on a vertical axis and having a beam pivoted on a horizontal axis to form a way for a traveling excavating bucket, the beam and the bucket being controllably moved through independent connections 25 from a single shaft. (4) To provide a device of this character in which the movements of the excavating bucket and the beam on which it travels are controllable independently of each other and from approximately the same point; also to provide means for moving the beam and its bucket bodily on a pivotal axis, with the operating mechanism for providing such movements in fixed 30 position. (5) To provide improvements of the support for the excavating bucket whereby the bucket may be positionable in parallelism with or angularly to the direction of length of the support for the bucket. (6) 35 To provide an improved excavating bucket adapted to permit of a dumping of the material at will. (7) To provide an improved mechanism for steadyng the device, said mechanism being movable into and out of an operative position without removal from the apparatus.

Other objects are to provide a device of this character which is composed mainly of metallic beams of ordinary cross-sectional configuration, to provide a built-up structure of exceeding strength and of few parts, all arranged compactly and of a strength adapted to withstand rough usage and the strains to which a device of this type is put; also to 55 provide a device which is simple and efficient in operation, durable in construction, readily

repaired, and which can be manufactured and installed at a relatively low cost.

To these, and other ends, the nature of which will be readily understood as my invention is hereinafter disclosed, said invention consists in the improved construction and combination of parts hereinafter fully described, illustrated in the accompanying drawings, and particularly pointed out in the appended claims.

In the accompanying drawings, in which similar reference characters indicate similar parts in each of the views Figure 1 is a view in side elevation of my device applied to the front of a portable engine, the excavator bucket and its supporting beam being shown as slightly raised. Fig. 2 is a front elevation of the same with the bucket and the supporting frame shown as swung to one side, the supporting beam being shown in substantially horizontal position. Fig. 3 is a view in side elevation similar to Fig. 1, with the bucket carrying beam raised and omitting the side supports for the device. Fig. 4 is a front elevation showing the parts on a slightly enlarged scale. Fig. 5 is a view partly in section showing the means for connecting the pull ropes to the drive shaft. Fig. 6 is a sectional view taken on the line 6-6 of Fig. 5. Fig. 7 is a horizontal sectional view of portions of the device showing the operating mechanism for operating the pull ropes or cables, and the means for providing the pivotal movements to the apparatus. Fig. 8 is a detail view showing the mechanism for controlling the movements of the mechanism by means of which the apparatus is moved pivotally. Fig. 9 is a detail view showing the excavating bucket in longitudinal section, and its mounting on the beam on which it is supported, the latter parts being shown in elevation. Fig. 10 is a top plan view of portions of the structure shown in Fig. 9. Fig. 11 is a sectional view taken on the line 11-11, Fig. 10. Fig. 12 is a detail view in elevation of a portion of the steadyng device. Fig. 13 is a plan view of the structure shown in Fig. 12. Fig. 14 is a sectional view taken on the line 14-14, Fig. 13. Fig. 15 is a sectional plan of a portion of the machine.

The present invention is designed more particularly as an attachment capable of being placed in position at the front or other convenient point of a suitable motor, preferably of a portable or traction steam engine.

type, the engine frame forming a support for two metallic beams 20 of any desired cross-sectional configuration and which extend longitudinally of the frame, as indicated in Fig. 1, being secured to the frame work of the motor in any desired manner. The forward ends of the beams are connected together by a cross-beam 21 which not only serves as a connecting and bracing member for said beams but also as a carrier for the pintle member 22 of a pivotal connection presently described, said pintle being positioned approximately midway of the distance between said beams, but spaced therefrom so as to place the pintle in advance of the cross-beam 21.

Secured to the beams 20 and extending vertically therefrom and spaced from the front ends thereof are vertical uprights 23 which are connected together at their upper ends by a suitable brace 24, these parts forming the rear frame of the apparatus. Extending vertically from said beams 20 at a point adjacent the front ends of said beams 25 are two-part uprights 25, each of said uprights extending in two vertical planes substantially parallel but spaced apart, the lower part of these uprights extending on a plane inside of the plane of the upper part, as indicated in Fig. 2, said parts being connected together by suitable plates or other connections 26, the structure being such as to provide a front frame for the apparatus, the lower part of which frame is of a length 35 between the upright portions less than the length between the upper portions of the uprights. Said uprights of the front frame are also connected at their tops by a brace 27. The two frames are connected by 40 braces 28.

Rising vertically in the plane of the front frame and intermediate the upright members forming said frame, are two spaced-apart bars or members 30 which are secured 45 to the top and bottom braces of said frame, and secured to the front of said bars or members adjacent the top brace 27 is one of the members of a top pivotal connection 31, presently described, the pintles of the top 50 connection 31 and pintle member 22 having their axes substantially in vertical alinement in order that the swinging portion of the apparatus presently described may be swung on a substantially vertical axis, which axis 55 corresponds to the axis of a circular member 32 positioned at the top of the apparatus and which is adapted to provide the turning movements of the shiftable portion of the apparatus.

60 The shiftable portion of the apparatus is connected to the frame work above described by means of the complementary members of the pivotal connections referred to, said complementary members being carried by a vertical upright 33 suitably formed, but prefer-

ably comprising two metallic bars spaced apart with the hinge members extending therebetween and secured in such position. The upper end of the upright 33 is provided with a horizontal member 34 to the top surface of which the circular member 32 is secured, said member 34 projecting forwardly beyond said circular member and having its forward end secured to and inclined to a beam or member 35 inclined to the vertical 75 and having its lower end secured to the lower end of the upright 33, said beam 35 being also preferably formed of metallic beams spaced apart, in order to provide strength with lightness. The upper end of 80 said beam or member 35 carries the sheave or pulley 36 over which one of the pull ropes or cables hereinafter referred to passes, the structure being such that said beam 35 retains its position relative to the vertical upright 33, regardless of the pivotal movements of the shifting apparatus.

Pivotal secured at the lower end of the upright 33 is the supporting beam or carrier 37 for the excavating bucket, said beam being preferably formed as indicated in Figs. 9, 10, and 11, consisting principally of a metallic beam preferably composed of two spaced-apart members secured together, the lower flanges of said beam forming a runway on which the bucket travels. The outer end of said beam is provided with a sheave or pulley 38 over which the pull rope or cable for the movements of the bucket passes. Said front end is also provided with 100 a suitable member such as an eye 39, to which the outer end of the pull rope or cable for controlling the movements of the beam 37 is secured in a suitable manner.

The parts heretofore described comprise 105 the main portion of the frame work of both the stationary and the shiftable portions of the derrick. As will be readily understood, the shiftable portion is so formed as to permit of a swinging or pivotal movement 110 bodily on the upper and lower pivotal connections 22 and 31, while the supporting beam 37 may be raised or lowered on its pivot while at the same time provision is made for moving the bucket 115 lengthwise of said beam, these being all of the movements of the swinging portion of a derrick required to perform the desired work, and the construction is such that the parts are of a maximum strength 120 without an increase in weight of material, while all of the parts are so braced as to withstand all strains, etc., to which they may be subjected in the operation of the apparatus.

125 The excavating bucket, designated as 40, is preferably formed as shown in Fig. 9, consisting of a bottom 41, pivotally connected with the forward end of a wall 42 rising vertically from the plane of the bot- 130

tom in closed position, said wall 42 extending around substantially three sides of the periphery of the bottom, leaving the front open, opposite sides being preferably inclined, as shown, the outer face of the wall 42 and the periphery of the bottom being on an approximate plane to provide a structure in which the bottom lies against the under edge of the wall 42. The bottom is 10 provided at its front with a plurality of teeth or fingers 43, which are adapted to act in advance of the front edge of the bottom in loosening the material being operated upon. The front edge of the bottom may be 15 straight or curved in its direction of length as may be desired, it being understood that the material taken up by the bottom in the movements of the bucket will be carried backward into the interior of the bucket, as 20 the latter is given its forward movement in operation.

The bucket is secured on the carrier beam 37 by means of a supporting frame comprising bars 44, secured at the rear of the 25 wall 42 and which project upwardly to permit of the formation of a bearing for a wheel 46 which is adapted to travel over the runway of the beam 37. A wheel 46 is mounted on the outer sides of the webs of 30 the composite beam 37, and in addition to this construction a further support is provided by a U-shaped frame 47 adapted to straddle the underface of the beam 37 and having its ends formed with bearings 35 adapted to carry wheels or rollers 48 which also travel on the runway of the beam at a point spaced from and in rear of the wheels 46. The U-shaped frame 47 is supported in proper position through suitable supports 49 40 extending from the lower portion of the wall 42 to the shaft for the roller 48, and additionally by means of an adjustable connecting rod 50, the rear end of which is carried by the shaft for the roller 48 while the forward end extends through an opening formed in an angle bracket 51 carried by the bar 44, the rod 50 having its forward end screw-threaded and being provided with nuts 52 located on each side of the bracket 50 51, this particular construction permitting of variations in the inclination of the bottom of the bucket in normal position, it being readily understood that an adjustment of the nuts 52 will cause the upper portion 55 of the bucket to be shifted longitudinally of the beam without affecting the position of the lower portion, thereby permitting the bottom to extend in a plane parallel or inclined to the direction of length of the beam, 60 as may be desired.

For the purpose of retaining the U-shaped frame or yoke 47 in position, I preferably connect it to the supports 49. This particular construction provides a carrier for the 65 bucket in which the weight of the load is

placed on both pairs of rollers or wheels, the weight on the forward pair 46 providing a downward pressure on the lower flange of the beam 37, while the rear pair of rollers 48 receive the thrust provided by the load 70 (the rollers 46 acting in the nature of a pivot for the entire bucket structure) and placing the pressure in an upward direction against the upper flange of the beam. Since the pairs of rolls are spaced a considerable distance apart, it will be readily understood that the leverage provided is such as to resist the pressure of the load, and at the same time to permit of a relatively free movement of the carriage formed by the two pairs of 80 rolls longitudinally of the beam, the result being that a maximum load can be manipulated in any desired manner without placing an excessive strain on the apparatus for providing such movements. The bottom, as 85 heretofore stated, is pivotally connected to the wall 42 at the forward ends of such wall. To retain it normally closed, I preferably form an opening at a suitable point at the bottom of the wall 42 and mount a spring 90 pressed catch member 53 at a point where its hook will engage a complementary member 54 carried by the bottom, this construction providing for a normal engagement of parts to retain the bottom closed. To permit the bottom to swing free a rope or cable 55 is secured to the catch 53 and led backward to a point convenient to the operator who, when he desires to dump the bucket, simply draws upon the rope or cable 55, and 95 releases the catch member 53 permitting the bottom to drop and dump the load. For the purpose of returning the bottom to its normal position after dumping, any suitable means may be provided, but I prefer to connect the bottom to the cable 55 by a short cable 56, the connections being such that when the bottom has been swung open the operator may draw upon the cable 55 and 100 swing the bottom to its normal position 110 where the catch members 53 and 54 will automatically engage. As the bottom swings forward upon the pivot at the forward end of the bucket, the cable 56 will be carried therewith. When the bottom is open and it 115 be desired to close it by pulling rearwardly upon the cable 55, it is obvious that the cable 56 will be carried therewith, the latter drawing the bottom to closed position and to a position where the bottom can be engaged by 120 the catch whereby the bottom will be maintained closed.

For the purpose of providing the various movements to the shiftable portion of the derrick I preferably provide the following: 125 57 designates a shaft extending laterally across the stationary frame and preferably in juxtaposition to the front upright frame, which shaft is provided with a drive pulley 58 connected to the motor in a suitable man- 130

ner. The shaft 57 extends entirely across the frame and is provided with a pair of wheels 59, 60 keyed or otherwise suitably secured, each of said wheels being peripherally beveled, as shown in Fig. 5, for the purpose of coöoperating with complementary members 61, 62 loosely mounted on the shaft, each of said members being in the form of a circular web having a flared periphery or 10 apron, said apron normally overlying its wheel 59 or 60, as shown in Fig. 5. The members 61 and 62 are loosely mounted on the shaft 57 and are adapted to be coupled together by movements axially of the shaft 15 provided by an arm 63 pivoted at one end to a bracket 64 and at its opposite end to a bell crank lever 65 through a link connection 66, the arm 63 being preferably formed as shown in Fig. 6, in order that it may encircle 20 the parts and permit of a loose engagement between the arm and a part 67 carried by or secured to the hub of the complementary member 61 or 62, as the case may be, the construction being such that movements of 25 the bell crank lever 65 will cause a frictional engagement or disengagement between the complementary members of the coupling indicated at 59 and 61 or 60 and 62, such engagement causing the member 61 or 62 to be 30 driven by the shaft 57, a release of such engagement destroying such drive connection. The hub of each of the members 61 and 62 is preferably provided with sprocket teeth for the purpose of driving a sprocket chain 35 adapted to operate suitable winding structure, a preferred type of which is shown in the drawing and which comprises a shaft 67 forming the drive shaft and on which a sprocket wheel 68 is mounted and connected 40 to the member 61 or 62, as the case may be. Said shaft is also provided with a pinion 69 adapted to engage with a gear 70 mounted on a shaft 71 carrying a winding drum 72 upon which the rope or cable is adapted to 45 be wound or unwound.

As heretofore set forth, there are two independent movements of parts, viz., a movement of the excavating bucket longitudinally of the beam 37, and a movement of the beam 37 on its pivot. Inasmuch as independent movements may be required, each movement is provided by a separate winding mechanism, and these winding mechanisms are preferably arranged as shown in Fig. 4, 50 the mechanism for moving the beam 37 on its pivot being preferably located above the shaft 57, while the mechanism for moving the bucket longitudinally of the beam is located below such shaft, this particular construction permitting of the use of the two driving members 59 and 60 on the same shaft and independently connectible to a winding mechanism, the sprocket connections being arranged on the outer sides of the coupling 55 devices.

73 designates the winding cable for the beam 37, said cable having one end secured to the eye 39, the cable passing over the sheave or pulley 36 and two idler pulleys 74 and 75 carried respectively by the upright 70 33 and members 30, to the winding drum 72 of the mechanism operated by the wheel 59 (the upper mechanism). 76 designates the winding cable for the bucket, which cable has its front end connected to 75 the base 44, as shown in Fig. 9, and is then carried forward to the end of the beam 37, over the pulley 38 and rearward over idler pulleys 77 and 78, respectively, to the winding drum 72 of the lower mechanism. By 80 this construction it will be seen that both of the cables 73, 76 are so arranged that the point on which the shiftable portion of the derrick is pivoted is so positioned as to have the axis of the pivotal connections extend through that portion of the two cables which lie between the pulleys 74 and 75 and the pulleys 77 and 78, respectively, so that the pulleys 75 and 78 do not change their positions during the swinging movements 85 of the derrick, while the pulleys 74 and 77 swing with the derrick and without affecting the cables, this shifting movement being possible without liability of the cables passing from the pulleys 74 and 77. 90

95 For the purpose of operating the two cable winding mechanisms previously described, I employ two levers 79 and 80, the former being connected to and adapted to operate a sleeve 81, suitably supported for 100 pivotal movement on the rear uprights, and carrying an arm 82 which is adapted to connect with the bell crank lever 65 through a link 83 of the mechanism for operating the lower winding mechanism, said lever 105 75 having a suitable latch device for retaining it in adjusted position. The lever 80 is connected to a shaft 84 extending through the sleeve 81 and connected to the bell crank lever of the upper winding mechanism in a manner similar to the connection of the sleeve 81 to its particular mechanism, the lever 80 also having latching mechanism for the purpose of retaining the parts in 110 adjusted position. 115

As will be seen by reference to Fig. 5, the member 61 is movable axially to place it in driven engagement with the wheel 59, the engagement providing a friction drive between the parts and serving to wind the 120 cable on the drum. When this frictional engagement is broken by moving the member 61 axially in the opposite direction, the entire winding mechanism is released and the cable is permitted to run out freely under 125 the weight of the parts connected to the cable. In order to retain the winding mechanism in a fixed position, I preferably employ one or more blocks 85, the inner faces of which are engaged by the member 130

61 when the latter is drawn away from the wheel 59 to its greatest extent, the movements of the lever 80 controlling the degree of pressure between the member 61 and the blocks 85, this latter provision being made for the purpose of providing either simply a brake mechanism or an absolute stop, depending upon the degree of pressure applied by the member 61 onto the face of the blocks 85. It is to be understood (and this will be apparent from Fig. 4) that a similar construction and operation is provided in connection with the wheel 60.

From the above description, it will be seen that when it is desired to provide a sequence of operations to the parts, all mechanism for providing these operations is controlled from a point where the services of but a single operator are required.

Owing to the many uses to which the device may be employed, and the many varieties of operations which may be practised, all of the descriptions of operations are not set forth; a few examples, however, are given.

After the apparatus has been moved into the desired location for the purpose of excavating by carrying the bucket vertically against a wall which may be found in front of the bucket, the beam 37 is lowered by releasing the holding mechanism provided by the lever 80 which allows the forward end of the beam to move downward to the desired point, at which point the lever 80 is again manipulated to bring the member 60 into tight frictional engagement with its holding blocks 85. The bucket, which has its bottom in closed position, is then moved forwardly on the beam 37 by actuating the lever 79 to throw the member 62 into contact with the wheel 60 and throwing the lower winding mechanism into operation. The bucket moves forwardly until it reaches a desired position and into contact with the wall which is being operated upon, whereupon both mechanisms may be brought into operation with the result that the beam 37 is moved vertically and at the same time the bucket is drawn toward the outer end of the beam, thus causing the bucket to penetrate the wall and at the same time to be moved upwardly therein until the bucket has been filled, whereupon the lever 79 may be manipulated to permit the bucket to reverse its direction of movement on the beam and be withdrawn from the wall. The beam 37 is then moved to a desired position for dumping the load and the bucket moved to a position where it will be positioned over the point where the load is to be dropped, such, for instance, as onto a wagon or other carrier, whereupon the operator draws upon the rope 55, releases the catch member 53 and permits the load to be dumped at such point. After dumping, the rope 55 is again

manipulated by the operator to close the bottom 41, whereupon by proper manipulation of the levers and the device for moving the apparatus pivotally (presently described) the parts are returned to a position ready to take up a new load.

As will be readily understood, the lever manipulations may be entirely separate from each other or combined, the two independent winding mechanisms being operable at will separately and entirely under the control of the operator so that one mechanism may be winding while the other is winding, stationary, or unwinding, thus providing a structure which is capable of the widest variations such as may be required under the many conditions of use to which apparatus of this character is put.

In order that the shiftable portion of the apparatus may be moved pivotally on its pivotal connections under the control of the operator, I preferably employ the following mechanism: Mounted on suitable braces connecting the rear uprights 23 is a vertically extending shaft 86, the upper end of which projects above the plane of the upper ends of said uprights and is provided with a sprocket wheel 87, with which a sprocket chain 88 co-operates, said chain having its ends connected to the periphery of the circular member 32, the construction being such that upon a rotation of the shaft 86, said member 32 will be given a pivotal motion on an axis extending in a plane corresponding to the axis of the pivotal connection for the shiftable portion of the apparatus. For the purpose of providing rotation of the shaft 86, I preferably employ power from the main drive shaft, through the medium of a worm and worm gear connection carried respectively by a shaft 89 and the shaft 86, as shown in Fig. 7, the shaft 89 carrying a wheel 90 located between the wheels 59 and 60 but positionable out of contact with both. The shaft 89 is mounted in a bearing 91 which is slidable on a suitable support so as to shift the wheel 90 into engagement with either of the wheels 59 and 60, the sliding movement of the shaft bearing being provided through a suitable lever connection shown in Fig. 8 in which a lever 92 is connected to the bearing through the medium of a link connection 93, the lever having a pawl structure by means of which the bearing may be held in any of its adjusted positions. By this particular construction, it will be understood that the normal position of the wheel 90 will be at a point out of contact with either of the wheels 59 or 60; in which position the shiftable portion of the apparatus is held against rotation by reason of the worm and worm gear structure which would prevent any shifting of such portion of the apparatus on its pivot. When it is desired to shift these parts, the lever 92 is operated to

move the bearing in proper direction to carry the wheel 90 into frictional engagement with either the wheel 59 or 60, depending upon which direction it is desired that the shifting portion of the apparatus shall move; when the desired position is reached the lever 92 is moved back to its initial position, thereby disconnecting the wheel 90 from its drive wheel (the wheel 59 or 60, as the case 10 may be), leaving the parts in their proper adjusted position.

As will be readily understood, the relative lightness of the apparatus employed compared with the heavy strains and pressures 15 placed thereon in operation, will tend to cause vibrations to the apparatus. To avoid these as much as possible, I preferably employ a steadyng apparatus by means of which lateral vibrations are reduced to the 20 minimum. The means for steadyng the apparatus comprises two devices which are substantially duplicates, one being secured to each side of the stationary portion of the apparatus. The specific structure of the 25 devices is illustrated more particularly in Figs. 2, 12, 13 and 14, and since the devices are substantially duplicates, a description of one will suffice.

Secured to the upright 25, at a point adjacent its top, are two plates 94, the lower ends of which are bolted to two spaced-apart bars 95 and to a brace member 96 extending laterally across and projecting outside of the uprights 25, the plates 94 and brace member 35 96 providing a stiff frame or support for the bars 95, each of which is provided with spaced-apart openings 97 to permit of adjustment in the position of the bars relative to the said frame. Adjacent to the lower 40 ends the bars 95 are connected together in spaced-apart relation by suitable straps 98. On the opposite edge of said bars, each is provided with inwardly extending projecting portions 99 which, in connection with the 45 straps 98, complete a slideway for an adjustable member or bar 100 having its lower end pivotally connected to a plate 101 preferably having its corners bent downwardly as shown in Figs. 12 and 13. At a suitable 50 point in the length of said bar 100 I preferably provide a plurality of ratchet teeth indicated at 102, which are adapted to be engaged by either one of two pawls 103 mounted on a pin 104 carried in brackets 105 positioned on the bars 95, said pawls being of 55 different length so as to permit of adjustment of the bar 100 in the direction of length of the bars 95 in relatively small distances without the necessity of a large number of ratchet teeth, thereby enabling of the formation of teeth of sufficient size to retain the parts in adjusted position. The plate 60 101 is also pivotally connected to a brace 106 which has its rear end pivotally connected to 65 the stationary frame of the apparatus, said

base being formed in two parts in the nature of a toggle device, one of the parts being of relatively short length.

In use, the parts are arranged as shown in full lines in Fig. 2, with the plate 101 in contact with the ground, the brace 106 having its parts in alinement; by manipulating the pawls 103, the proper adjustment as to length between the ground and the upper end of the steadyng device is secured with 75 sufficiently close accuracy as to prevent lateral swaying of the apparatus in use. When it is desired to release the steadyng device, it is necessary only to release the engagement between the active pawl 103 and the 80 rack formed by the ratchet tooth 102, whereupon the bar 100 may be moved longitudinally of the bars 95 to the position shown in dotted lines in Fig. 2, the brace 106 having its form changed to permit it to assume the 85 position shown in said dotted lines. This latter position removes the steadyng device to an out of the way position. As these devices are duplicated on opposite sides of the apparatus, it will be readily understood 90 that the apparatus is firmly held against lateral swaying or substantial vibratory movement and by reason of its presence, provides an apparatus structure relatively light and of a minimum weight. This particular 95 structure is especially adapted for use in connection with apparatus being used where the ground is not hard and where there is a tendency of the apparatus to sink. In such case the swinging of the beam 37 laterally has the effect of causing a pressure to be placed on the side to which the beam is being swung. When this action takes place, if the surface of the ground on which the plate 101 rests is not sufficiently hard to sustain such pressure, the plate will tend to sink under this pressure and upon the return movement of the beam, which has the effect of releasing a portion of this pressure, the upper portion of the apparatus will tend to draw the outer casing provided by the 100 members 95 upwardly relatively to the bar 100 thereby permitting a pawl to engage a different notch and thus automatically take up for any sagging or sinking of the plate 115 in use, so that in operation any tendency of the apparatus to rock due to the sinking of the plates will be corrected and practically eliminated by the successive operations of the beam in this respect, thus eliminating 120 any requirement for the use of jacks or any similar mechanism for the purpose of retaining the parts steady.

While I have herein presented and described a preferred form for carrying my 125 invention into effect, I am aware that changes and modifications therein may be made and may be found necessary to suit the various exigencies of use, and I reserve the right to claim any and all such changes 130

and modifications as may be found necessary and advisable, so long as such changes and modifications fall within the spirit and scope of the invention as expressed in the 5 appended claims.

Having thus described my invention, what I claim as new is:—

1. In excavating apparatus, a frame pivoted on a vertical axis, a bucket support 10 pivoted thereto on a horizontal axis and having its outer side faces formed to provide a runway longitudinally of the support, an excavating bucket having rollers mounted in said runways, said rollers being located in 15 rear of and spaced from said bucket.
2. In excavating apparatus, a frame pivoted on a vertical axis, a bucket support pivoted thereto on a horizontal axis and having its outer side faces formed to provide a runway 20 longitudinally of the support, an excavating bucket having rollers mounted in said runway, said rollers being arranged in pairs spaced apart in the direction of length of the runway and positioned in rear of the 25 bucket.
3. In excavating apparatus, a frame pivoted on a vertical axis, a bucket support pivoted thereto on a horizontal axis and having its outer side faces formed to provide a runway 30 longitudinally of the support, an excavating bucket having rollers mounted in said runway, said rollers being arranged in pairs spaced apart in the direction of length of the runway, and means for adjusting the 35 distance between the pairs of rollers, said ad-

justment controlling the relationship of the lines corresponding to the direction of length of the bucket and of the support.

4. In excavating apparatus, a frame pivoted on a vertical axis, a bucket support pivoted thereto on a horizontal axis and having its outer side faces formed to provide a runway longitudinally of the support, an excavating bucket having arms connected respectively to the top and bottom of the rear 40 of the bucket, the lower arms extending rearwardly at an angle to place the rear ends at a point in rear of and spaced from the other arms, each of said arms carrying a roller, and adjustable connections between said 45 arms.

5. In an excavating apparatus, an excavating bucket having a bottom pivoted adjacent the front of the bucket and being provided with forwardly extending fingers, a 50 catch device at the rear of the bucket and adapted to normally hold the bottom in place, and an operating pole rope connected to said catch device and adapted to release the bottom at will, said rope being also 55 loosely connected to the bottom for the purpose of swinging the latter to its normal position after being opened.

In testimony whereof I affix my signature in the presence of two witnesses.

LEROY P. CLUTTER.
